UNITED STATES PATENT OFFICE.

CHARLES BOCCIA, OF NEW YORK, N. Y.

DESIGN FOR A TOOTH-BRUSH.

47,100.

Specification for Design.

Patented Mar. 16, 1915.

Application filed November 10, 1914. Serial No. 871,404. Term of patent 14 years.

To all whom it may concern:

Be it known that I, CHARLES BOCCIA, a citizen of the United States, residing at New York city, in the county and State of New York, have invented a new, original, and ornamental Design for Tooth-Brushes, of which the following is a specification, reference being had to the accompanying drawing, forming part thereof.

Figure 1 in the drawing is a perspective

view showing my design of tooth brush. Fig. 2 is an end elevational view thereof.

I claim:

The original design for tooth brush, as shown.

CHARLES BOCCIA.

Witnesses:

JOHN A. DONEGAN,
GEO. A. BYRNE.
